UNITED STATES PATENT OFFICE.

DAVID M. GALLAGHER, OF ANSONIA, CONNECTICUT, ASSIGNEE TO THE BASSETT METAL GOODS COMPANY, INC., OF DERBY, CONNECTICUT, A CORPORATION OF CONNECTICUT.

LIFT CATCH.

Application filed February 25, 1928. Serial No. 256,873.

My invention relates to lift catches for hand bags and other containers.

An object of the invention is to provide a novel and improved lift catch of this character.

Another object of the invention is to provide a lift catch of this character which is of simple, cheap, strong and durable construction, which may be easily assembled 10 and attached to the container, and which operates easily and smoothly.

The several features of the invention, whereby these and other objects may be attained, will be clearly understood from the 15 following description and accompanying drawings, in which,

Figure 1 is a side view of the upper portion of a hand bag to which my improved lift catch has been applied;

20 Fig. 2 is a longitudinal sectional view of the lift catch and a portion of the bag, the lift catch being shown in closed position;

Fig. 3 is a similar view but showing the lift catch in open position;

25 Fig. 4 is a transverse sectional view taken on the line 4—4 of Fig. 2;

Fig. 5 is a bottom plan view of the lift catch before attachment to the container;

30 Fig. 6 is a sectional view taken on the line 6—6 of Fig. 5 but showing the lift catch attached to the container; and

Fig. 7 is a view in perspective of the base member of the catch.

In the drawings my improved lift catch 35 is shown applied to a common type of hand bag 2 having the usual inner and outer U-shaped frame members 4 and 6 that are respectively provided with the usual registering slots 8 and 9 for receiving the catch member of the device.

40 As shown, the component parts of the lift catch consist of a base 10, a lift member 12, a catch member 14, and a leaf spring 16.

The base 10, which is made of sheet metal, 45 is provided with a top wall 18 having a clearance slot 20, side walls 22, and end walls 24 having depending tongues 26 for securing the base member to the outer frame member 6. The top wall of the base has downwardly and outwardly beveled end portions 28.

50 The lift member 12, which is also made of sheet metal, is provided with a top wall 30, side walls 32 and an end wall 34, the opposite end of the top wall being bent upwardly and

the corresponding ends of the side walls 55 being beveled downwardly and inwardly so as to permit said end of the lift member to be conveniently grasped in opening and closing the lift catch. The end portion of the top wall of the lift member extending from 60 the end wall 34 is inclined correspondingly to the adjacent beveled portion 28 of the top wall of the base. The end wall 34 of the lift member is provided with a suitable slot 38 for receiving one of the depending tongues 65 26 on the base, the slot being formed by inwardly projecting tongues 40 that are arranged inside of the side walls of the base.

The catch member 14 may be of a common construction having its upper end riveted or 70 otherwise secured to a U-shaped plate 42 which is suitably secured to the top and side walls of the lift member.

The leaf spring 16 is curved in an arc, as shown, and has one end received in the space 75 provided between a downwardly bent tongue 44 at one end of the clearance slot 20 in the base and the adjacent portions of the top wall of the base. The other or free end of the spring 16 is received in a suitably arranged notch in the catch 14 near the upper end thereof.

In assembling the parts of the lift catch, the base is placed within the lift member with the securing tongue 26 extending through the slot between the tongues 40 on the lift member, and with the catch 14 extending through the clearance slot 20 in the base. One end of the leaf spring 16 is inserted in the V-shaped notch provided by the lug 44, and its other 80 end is forced downwardly by means of a suitable tool into the retaining notch in the catch 14.

After the parts of the lift catch have been thus assembled, the securing tongues 26 of the base are inserted through apertures in the outer frame member 6 and bent inwardly and upwardly against the under side of the frame member in the usual manner so as to securely hold the lift catch in place.

With this construction it will be apparent that upon closing the lift member 12 so as to project the catch 14 through the slots 8 and 9 in the frame members, the leaf spring 16 will firmly hold the lift member 12 down upon 100 the base 18, and upon raising the lift member 12 the spring will likewise hold the lift member in open position, the free end of the

leaf spring being shifted to opposite sides of its dead center with relation to the axis of the lift member. Also, as the lift member approaches both its open and closed positions, the spring, as its end passes its dead center, will act to snap the lift member into these positions. The upward movement of the lift member is limited by the engagement of the head of the catch 14 with the 10 under side of the top wall of the base, and the downward movement of the lift member is limited by the top wall of the base. It will be apparent that the leaf spring 16 is so arranged as to yieldingly press the lift member longitudinally in such a manner as to maintain the parts of the pivotal connection as above described in proper pivotal engagement, and these parts are so arranged that there is no danger of them becoming jammed 20 or displaced upon attaching the lift catch to the container by means of the securing tongues 26.

As will be evident to those skilled in the art, my invention permits various modifications without departing from the spirit thereof or the scope of the appended claims.

What I claim is:

1. A lift catch for bags and other containers having, in combination, a base for 30 attachment to the container, a lift member, a tongue and slot connection between the base and lift member providing a pivotal connection to permit the lift member to be swung upwardly from and downwardly upon the base, a spring suitably arranged to hold the lift member in either of said positions and to press the lift member longitudinally in a direction from the pivoted end thereof toward its other end, and a catch carried by the 40 lift member.

2. A lift catch for bags and other containers having, in combination, a base having side and end walls, means comprising a tongue depending from one of the end walls 45 for securing the base to the container with the lower edges of the side walls substantially engaging the container, a lift member having a top wall, side walls and an end wall, said end wall having a slot through which 50 said tongue extends to provide a pivotal connection to permit the lift member to be swung downwardly over and upwardly from said base, a depending catch carried by said lift member, means comprising a spring having one end connecting with said base in 55 proximity to said pivotal connection and its other or free end engaging said catch, said spring being suitably arranged with relation to the axis of said lift member to cause its 60 free end to pass through a dead center as the lift member is moved from one to the other of said positions.

3. A lift catch for bags and other containers having, in combination, a base hav-

ing side and end walls, means comprising a 65 tongue depending from one of the end walls for securing the base to the container, a lift catch having a top wall, side walls and an end wall, said end wall having a slot through 70 which said tongue extends to provide a pivotal connection to permit the lift member to be swung downwardly over and upwardly from said base, a depending catch carried by said lift member, and means comprising a 75 spring having one end connected with said base in proximity to said pivotal connection and its other or free end connected with said lift member and suitably arranged with relation to the axis of said lift member to cause its free end to pass through a dead center as 80 the lift member is moved from one to the other of said positions.

4. A lift catch for bags and other containers having, in combination, a base having a top, side and end walls, and means comprising a tongue depending from one of the end walls for securing the base to the container, a lift member having a top wall, side walls and an end wall, said end wall being 90 provided with inwardly projecting tongues 95 that are spaced apart to provide a slot between them through which the tongue on said base extends to provide a pivotal connection to permit the lift member to be swung downwardly over and upwardly from said base, a depending catch carried by said lift member, and means comprising a spring connecting said lift member and base for holding 100 said lift member in either of said positions and suitably arranged to yieldingly press said lift member in a direction to maintain the end wall of said slot substantially against said depending tongue on the base member.

5. A lift catch for bags and other containers having, in combination, a base having top, side and end walls, a tongue depending from one of the end walls for securing the base to the container, a lift member having a top wall, side walls and an end wall, said end wall being provided with inwardly 110 projecting tongues spaced apart to provide a slot through which said tongue on the base extends to provide a pivotal connection to permit the lift member to be swung downwardly over and upwardly from said base, a 115 depending catch on the lift member, and means comprising a spring having one end connected with said base in proximity to said pivotal connection and its other end connected with said catch and suitably arranged 120 with relation to the axis of the lift member to cause its last mentioned end to pass through a dead center as the lift member is moved from one to the other of said positions.

In testimony whereof, I have signed my 125 name to this specification Feb. 23, 1928.

DAVID M. GALLAGHER.
